UNITED STATES PATENT OFFICE.

JULIUS R. HALL, OF OAK PARK, ILLINOIS, ASSIGNOR TO BOOTH-HALL COMPANY, OF CHICAGO, ILLINOIS, A CORPORATION OF ILLINOIS.

FURNACE-DOOR.

1,286,604.

Specification of Letters Patent.

Patented Dec. 3, 1918.

Application filed April 4, 1918. Serial No. 226,576.

To all whom it may concern:

Be it known that I, JULIUS R. HALL, a citizen of the United States, residing at Oak Park, in the county of Cook and State 5 of Illinois, have invented a new and useful Improvement in Furnace-Doors, of which the following is a specification.

This invention relates particularly to doors for electric furnaces.

10 The primary object is to provide a furnace door equipped with an electrode-holder, which is durable and well adapted to its purpose and permits manipulation of the electrode in a desirable manner.

15 A further object is to provide an electric furnace with an electrode-supporting door of the character indicated, which may be termed an auxiliary door, and to provide the furnace with a main door for the same 20 opening, said doors being mounted to swing out of the path of each other, so that either door may be used to close the door-opening.

It may be stated preliminarily that the 25 construction herein described is particularly desirable in electric furnace construction wherein there is employed an auxiliary electrode adapted to be temporarily used in preliminarily heating the furnace, that is, in heating the furnace until the bottom or 30 wall-contacts become sufficiently conductive to carry the current, after which the auxiliary electrode may be withdrawn. In the construction illustrated, the main door is retracted or moved to an inoperative position and the auxiliary door is moved to the closed position and serves to hold the auxiliary electrode in the furnace during the preliminary heating operation, after which the auxiliary door is moved to the inoperative 35 position out of the path of the main door, and the main door is therupon closed and the operation of the furnace proceeds, the current now being carried wholly by the main electrode or electrodes and the body or 40 wall-contacts or electrodes which are rendered conductive by the preliminary heating operation.

The invention is illustrated in its preferred embodiment in the accompanying 45 drawings, in which—

Figure 1 represents a broken plan view of an electric furnace constructed in accordance with the invention; Fig. 2, a broken elevational view of the same, this view, as well 50 as the preceding view, showing the main

door in the inoperative position and the auxiliary door in operative position; Fig. 3, a broken vertical sectional view showing the construction of the auxiliary door, that is, the door carrying the auxiliary electrode; Fig. 4, a broken section taken as indicated at line 4 of Fig. 3; Fig. 5, a broken sectional view taken as indicated at line 5 of Fig. 3; and Fig. 6, a plan sectional view taken as indicated at line 6 of Fig. 5.

In the construction illustrated, A represents the body of the furnace, whose vertical wall is provided with a door-opening A¹; A², a door-opening-frame secured to the vertical wall of the furnace-body; B, a vertically-movable counter-balanced main door adapted to close the door-opening A¹ and also to be swung to a position above the door-opening and out of the path of the auxiliary door; C, an auxiliary door adapted to be swung to a position to one side of the door-opening A¹ and out of the path of the main door; C¹, an electrode-supporting-frame mounted on the auxiliary door C; C², an electrode-holder or clamp movably mounted on the frame C¹, on which frame the member C² is adapted to travel and tilt; and C³, an electrode carried by the clamp C² and adapted to extend through an opening in the door C.

The furnace-body A may be of any suitable construction. It is usual to so mount the furnace-body that it can be tilted. This feature is not illustrated, as it forms no part of the present invention.

The furnace may be provided in its bottom wall with a wall-contact having a refractory facing which becomes conductive when hot, as described, for instance, in Patent No. 1,244,415, granted October 23, 1917, on the application of William K. Booth. The furnace may also be provided with one or more main electrodes depending through the dome of the furnace, as illustrated in said patent, and the auxiliary electrode herein illustrated may be used in accordance with the invention disclosed in said patent, that is, the auxiliary electrode herein shown may be of the same polarity as the wall-contact (not shown) which is employed in the bottom of the furnace. The main electrode, or main electrodes which depend through the top wall of the furnace, may be mounted in any suitable manner. They may be mounted, for instance, in the

manner illustrated in my co-pending application No. 220,702, filed March 6, 1918.

The furnace-body A comprises preferably a steel shell 1 and a refractory lining 2 through which the door-opening A¹ extends. The door-frame A² may be of any suitable construction. In the form shown it comprises a cast-metal annulus 3 and a detachable insert-plate 4 at the upper portion of said annulus, adapted to be replaced by a new insert plate, according to necessity.

The main door B may be of any suitable construction. In the construction illustrated, the door B is adapted to be carried from the closed to the open position shown in Fig. 2 by parallel movement. It is equipped with lateral pivots 5 which are supported in arms or lugs 6 carried by the intermediate portion of a yoke 7 which has its arms connected by pivots 8 to the furnace-body. The extremities of the arms of the yoke 7 are equipped with counter-weights 9. The door B may be of sufficient weight to cause it to tend to move to the door-closing position against the resistance of the counter-weights 9; and a latch device comprising a link 10 provided with a series of perforations and a loop or guide 11 provided with a corresponding perforation and adapted to receive a pin 12 may serve to hold the main door temporarily in elevated position and out of the path of the auxiliary door.

The door C preferably comprises a casting having a water-cooled portion 13 which is adapted to extend into the door-opening, the door thus having a water-chamber 14 with which communicate flexible pipes 14^a, providing for water circulation. The door C is provided at its upper edge portion with a deep recess 15 which has an inclined bottom wall 15^a, upon which the inclined auxiliary electrode C¹ may rest. The door C is, in the illustration given, equipped with arms 16 which may be cast integrally with the door. These arms extend to a point distant from one lateral edge of the door-opening and have their extremities equipped with a sleeve or pivot portion 16^a, which may be cast integrally with the arms. This sleeve is fixedly secured to a vertical pintle or shaft 17 which is mounted in bearings 18 secured to the shell of the furnace-body. The sleeve 16^a is rigidly secured to the shaft 17, as by means of a set-screw 19.

The electrode mounting or frame C¹, which really constitutes an incline extension of the auxiliary door C, preferably comprises a casting 20 which is provided with inclined guide flanges 20^a, and which has its inner end equipped with lugs 20^b detachably secured to the arms 16 which are extended across the outer face of the door C, with which said arms 16 are integrally

formed; an inclined rack 20^c disposed between the guide flanges 20^a and secured to the upper wall of the casting 20; and a pair of hooks 20^d secured to the outer end of the casting 20 and adapted to serve as pivotal supports for the electrode-clamp C² to enable the electrode to be tilted to a vertical position with its inner or hot end elevated, after the electrode is withdrawn from the furnace.

The electrode-holder or clamp C² comprises a slide 22 adapted to the guide-flanges 20^a, and a split clamping-ring 22^a through which the electrode C¹ extends and is adjustable. The slide 22 is provided beneath the electrode with a transverse bearing 22^b in which is journaled a shaft 23 which is equipped with a pinion 23^a which meshes with the rack 20^c. One end of the shaft 23 is equipped with an actuating wheel 23^b. The slide 22 is equipped with a laterally-projecting arm 24, with which is securely connected a flexible conductor 24^a, which may comprise a laminated copper-band.

The conductor 24^a depends from the arm 24, as shown in Fig. 4, and extends to a considerable distance below the level of the door C, as will be understood from Fig. 5. It is then bent forwardly to form a loop 24^b (Figs. 5 and 6) and is then bent upwardly as indicated at 24^c. The extremity 24^c is connected with an arm 25 of a switch which has a sleeve portion 25^a firmly secured to a downward extension of the shaft 17, the sleeve 25^a being also equipped with a knife-arm 25^b which works between the furcations 26 of a connection 27 which is secured to the shell of the furnace, thus placing the auxiliary electrode C¹ in electrical connection with said shell and thus with the wall-contact or contacts (not shown) with which the furnace-body is equipped. It will be understood that the loop 24^b of the conductor 24^a is of sufficient dimensions to compensate for the movement of the electrode-holder C² on its guides. From Figs. 5 and 6 it will be understood that when the auxiliary door C is swung to the open position the switch secured to the pivot-shaft 17 will be disconnected, so that the auxiliary electrode will be thrown out of the electric circuit.

It will be noted, from Fig. 3, that the guide-flanges 20^a are discontinued at the points 20^e. The hooks 20^d are open toward the electrode-holder C², and are adapted to receive the shaft 23 when the slide 22 is moved to the upper, outer end of its traverse. When this occurs, the slide becomes disconnected from the guide-flanges 20^a, and the operator, by depressing the outer end of the electrode, may swing the electrode to the vertical position indicated by dotted lines in Fig. 3, in which position it may be secured by means of a hook 28, which is pivotally connected with the outer end of the cast-

ing 20 and which is adapted to engage a perforate lug 28^a with which the slide 22 is equipped.

The manner of use will be readily understood from the description given. To prepare the furnace for operation, the charge is introduced through the door A¹, while the main door B is in the elevated position and the auxiliary door C is in a position at one lateral side of the door-opening. When the furnace is to be set in operation, the auxiliary electrode-holder C² is swung from the dotted position shown in Fig. 3 to a position parallel with the full-line position shown in Fig. 3; and by means of the hand-wheel 23^b the pinion 23^a is caused to operate on the arm 24 and shift the electrode-holder C² to the position shown in full lines in Fig. 3. In this movement, the shaft 23 moves out of the hooks 20^a and the slide 22 passes on to the guides 20^b, so that when the electrode-holder C² is in the operative position it will be firmly held on the guides. The auxiliary electrode-holder C³ is then adjusted in the holder C² until its inner end comes in contact with the charge in the furnace. In the operation of swinging the door C to the closed position, the switch comprising the arms 25 and 25^b is thrown to the connecting position, thereby throwing the electrode C³ into circuit with the wall-contact, or wall-contacts, of the furnace. In the operation, the current will pass from the main electrode or electrodes depending through the dome of the furnace to the auxiliary electrode C³, it being understood that in this operation the main electrode or electrodes are so adjusted as to afford arcs between their lower ends and the charge, so that the metal or material will be fused and form a pool at the bottom of the furnace, thus heating the lining of the furnace until the refractory facings of the wall-contacts become sufficiently heated to constitute good conductors, whereupon the current will be divided between the wall-contacts and the auxiliary electrode, which are of the same polarity. When the wall-contacts become operative, the auxiliary electrode C³ may be withdrawn and swung to the vertical position shown in dotted lines in Fig. 3, after which the auxiliary door may be swung to the inoperative position at one lateral side of the door-opening. The main door may then be lowered from the upper side of the door-opening to the closing position. In this closing movement, the main door B slides across the frame A² of the door-opening, and is firmly wedged between the intermediate portion of the yoke 7 and the frame A²; and by reason of the fact that the door B is pivotally suspended on the yoke, it will adjust itself to the outer surface of the frame A² of the door-opening, against which it is in effect wedged, affording a close joint. The opera-

tion of the furnace proceeds until the charge is melted; and when the charge is disposed of and a fresh charge introduced, the mode of operation described is repeated to preliminarily heat the furnace and thus enable the wall-contacts to become operative.

It will be understood from the description given that the main door and auxiliary door may be alternatively used to close the door-opening A¹; that the doors swing clear of each other to enable either door to be moved to the operative position; that the auxiliary door serves as a part of the supporting means for the auxiliary electrode, and is provided with connections for water circulation; regardless of the position of the auxiliary door; that the circuit for the auxiliary electrode is automatically made in the operation of swinging the auxiliary door to the closed position and is broken in the operation of swinging the auxiliary door to the inoperative position; and that the electrode-clamp is shiftably and tiltably mounted on its supporting frame, so that after withdrawal of the electrode it may be swung to the vertical position with the heated end of the electrode uppermost.

The foregoing detailed description has been given for clearness of understanding only, and no unnecessary limitation should be understood therefrom, but the appended claims should be considered as broadly as permissible in view of the prior art.

What I regard as new and desire to secure by Letters Patent is—

1. In means of the character set forth, the combination of a furnace-wall provided with a door-opening, and a door adapted to said opening equipped with electrode-supporting means.
2. In means of the character set forth, the combination with a furnace-wall provided with a door-opening, of a door adapted to said opening and mounted to be moved to a position away from said opening, and an electrode-holder movably mounted on said door.
3. In means of the character set forth, the combination with a furnace-wall provided with a door-opening, of a door adapted to said opening and mounted to be moved to a position away from said opening, and an electrode-holder shiftably and tiltably mounted on said door.
4. In means of the character set forth, the combination with a furnace-wall provided with a door-opening, of a door adapted to said opening and mounted to be swung to a position away from the opening, an extension on said door, equipped with a guide, a slide mounted on said guide and equipped with electrode-clamping means, and means for moving said slide on said guide.
5. In means of the character set forth, the combination with a furnace-wall provided

with a door-opening, of a door adapted to said opening and mounted to be swung to a position away from said opening, an extension on said door equipped with a guide, a slide mounted on said guide and equipped with electrode-clamping means, and rack and pinion means adapted to move said slide on said guide.

6. In means of the character set forth, the combination with a furnace-wall provided with a door-opening, of a door adapted to said opening and mounted to be moved to a position away from said opening, a shiftable electrode-holder carried by said door, and means whereby said electrode-holder may be shifted and tilted.

7. In means of the character set forth, the combination with a furnace-wall provided with a door-opening, of a door adapted to 20 said opening and mounted to permit it to be moved to a position away from the door-opening, a guide extending outwardly from said door, a slide adapted to move on said guide and to be disconnected therefrom, said 25 slide being equipped with electrode-holding means, and means whereby said slide may be tilted to swing the electrode to an upright position.

8. In means of the character set forth, the combination with a furnace-wall provided with a door-opening, of a door adapted to said opening and mounted to be moved to a position away from the opening, an electrode mounted on said door, and electric connections for said electrode, including a switch actuated in the opening and closing movements of said door.

9. In means of the character set forth, the combination with a furnace-wall provided 40 with a door-opening, of a door adapted to said opening and mounted to be moved to a position removed from the opening, an electrode-holder movably mounted on said door, a switch having a member adapted to be 45 actuated in the opening and closing of said door, and a flexible conductor between said electrode-holder and said switch.

10. In means of the character set forth, the combination with a furnace-wall provided 50 with a door-opening, of a door adapted to said opening and mounted to be swung to a position away from the door-opening, a guide projecting outwardly from said door, an electrode-holder shiftably mounted on 55 said guide, and means at the outer end of said guide for pivotally supporting said electrode-holder.

11. In means of the character set forth, the combination with a furnace-wall provided 60 with a door-opening, of a door adapted to said opening and mounted to be swung to a position away from the door-opening, a guide projecting outwardly from said door, an electrode-holder shiftably mounted on 65 said guide, means at the outer end of said

guide for pivotally supporting said electrode-holder, and means for securing the electrode-holder in tilted position.

12. In means of the character set forth, the combination with a furnace-wall provided 70 with a door-opening, of a door adapted to said opening and mounted to be swung to a position removed from the opening, an extension carried by said door and provided with a guide and rack and equipped also with hooks, 75 an electrode-holder mounted on said guide and adapted to be disconnected therefrom at the outer end of the traverse, and a shaft journaled in said slide and equipped with a pinion working in said rack, said shaft 80 adapted to engage said hooks and serve as a pivot for the electrode-holder.

13. In means of the character set forth, the combination with a furnace-wall provided with a door-opening, of a door adapted to 85 said opening and mounted to be swung to a position removed from the opening, an extension carried by said door and provided with a guide and rack and equipped also with hooks, an electrode-holder mounted on 90 said guide and adapted to be disconnected therefrom at the outer end of the traverse, a shaft journaled in said electrode-holder and equipped with a pinion working in said rack, said shaft adapted to engage said hooks 95 and serve as a pivot for the electrode-holder, and means for securing the electrode-holder in tilted position.

14. In means of the character set forth, the combination with a furnace-wall, provided with a door-opening, of a door adapted to said opening and provided with an opening through which an electrode may extend, an extension detachably carried by said door and an electrode-holder movably mounted on said extension.

15. In means of the character set forth, the combination with a furnace-wall provided with a door-opening, of a door adapted to said opening and provided with an 11 opening through which an electrode may extend, an extension detachably carried by said door, and an electrode-holder shiftably and tiltably mounted on said extension.

16. In means of the character set forth, the combination with a furnace-wall provided with a door-opening, of a door adapted to said opening and equipped with laterally-extending arms, a pivot mounted on the 1 furnace-wall and rigid with said arms, a switch carried by said pivot, an electrode-holder movably mounted on said door, and a flexible electric conductor between said electrode-holder and switch.

17. In means of the character set forth, the combination with a furnace-wall provided with a door-opening, of a door adapted to said opening and equipped with laterally-extending arms, a pivot mounted on the 1

furnace-wall and rigid with said arms, a switch carried by said pivot, an electrode-holder shiftably and tiltably mounted on said door, and a flexible electric conductor 5 between said electrode-holder and said switch.

18. In means of the character set forth, the combination with a furnace-wall provided with a door-opening, of a door adapted to said opening and mounted to be moved to a position removed from the door-opening, means for circulating water through said door, regardless of the position of the door, and an electrode-holder mounted on 15 said door.

19. In means of the character set forth, the combination with a furnace-wall provided with a door-opening, of a door adapted to said opening and mounted to be moved 20 to a position removed from the door-opening, means for circulating water through said door, regardless of the position of the door, and an electrode-holder movably mounted on said door.

25 20. In means of the character set forth, the combination with a furnace-wall provided with a door-opening, of a door adapted to said opening, arms formed integrally with the outer surface of said door and projecting laterally from one edge of the door, pivotal connections between said arms and the furnace-wall, an extension equipped with a guide and provided with lugs, pins connecting said lugs with said arms at the outer 35 surface of said door, an electrode-holder movably mounted on said guide, and means for shifting said electrode-holder.

21. In means of the character set forth, the combination with a door-opening, of a 40 door adapted to said opening and mounted to be moved to a position removed from the opening, an inclined guide extending outwardly from said door, and an electrode-holder shiftably mounted on said guide.

45 22. In means of the character set forth,

the combination with a furnace-wall provided with a door-opening, of a door adapted to said opening and mounted to be moved to a position removed from the opening, an inclined guide extending outwardly from 50 said door, an electrode-holder shiftably mounted on said guide, a rack associated with said guide, and a pinion mounted on said electrode-holder and meshing with said rack and equipped with actuating means. 55

23. In means of the character set forth, the combination with a furnace-wall provided with a door-opening, of a door adapted to said opening and mounted to be moved to a position removed from said opening, an 60 inclined guide extending outwardly from said door, an electrode-holder mounted on said guide, and means whereby said electrode-holder may be shifted to the outer end of the guide and secured thereat in 65 tilted position with relation to the guide.

24. In means of the character set forth, the combination with a furnace-wall provided with a door-opening, of a main door and an auxiliary door adapted to close said opening, said doors having mountings adapting each door to be moved out of the path of the other door and said auxiliary door being equipped with electrode-holding means. 70

25. In means of the character set forth, the combination with a furnace wall provided with a door-opening, of a main door adapted to close said opening, a mounting for said door adapted to carry the door to 75 and support it in position above said door-opening, an auxiliary door adapted to close said door-opening, said auxiliary door equipped with electrode-holding means, and a mounting for said auxiliary door 80 adapted to carry the same to and support it in position at one lateral side of, said door opening. 85

JULIUS R. HALL.
